VALVE SPRING COMPRESSOR

Filed Sept. 19, 1927

UNITED STATES PATENT OFFICE.

LOUIS TOUCHETTE, OF MINNEAPOLIS, MINNESOTA.

VALVE-SPRING COMPRESSOR.

Application filed September 19, 1927. Serial No. 220,515.

My invention has for its object to provide an extremely simple and highly efficient valve spring compressor. While the improved tool is well adapted for use in the removal and replacement of the spring of a valve, such as the puppet valve of an internal combustion engine, it is especially well adapted for use in the replacement of such a spring in inaccessible places such as back of a skirt or other extension or obstruction on a cylinder block.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

20 Fig. 1 is a fragmentary view partly in side elevation and partly in vertical section showing the improved spring compressor applied to one of the valve springs in a Ford automobile engine;

25 Fig. 2 is a fragmentary detail view with some parts sectioned on the line 2—2 of Fig. 1;

30 Fig. 3 is a fragmentary detail view with some parts sectioned on the line 3—3 of Fig. 1 with the tool shown in a different position by means of broken lines;

35 Fig. 4 is a perspective view of the short jaw of the tool;

Fig. 5 is a bottom plan view of the long jaw of the tool; and

Fig. 6 is a perspective view of the grapple removed from the tool.

Of the parts of the Ford automobile engine illustrated, it is important to note the block 40 7, cylinder wall 8, intake chamber 9, crank case 10, spring chamber 11, skirt 12 at the outer face of the chamber 11 to which a cover plate, not shown, is applied, upper and lower axially aligned bosses 13 and 14, respectively, 45 in the spring chamber 11, valve 15 and its stem 16 working through the boss 13, tappet 17 and its stem 18 working through the boss 14 with its upper end arranged to engage the lower end of a valve stem 16, cam 19 in the crank case 10 for operating the tappet 17, and a valve spring 20 encircling the valve stem 16 and the boss 13 and compressed between the top of the spring chamber 11 and a

washer 21 applied to the valve stem 16 and held in place by a pin 22.

55 The improved spring compressor is in the form of a pair of tongs comprising a pair of crossed levers, one of which is provided with a fixed laterally projecting pivot stud 23 and the other of which is provided with, as shown, 60 two longitudinally spaced open notch-like seats 24 either one of which is adapted to receive said stud and pivotally connect said levers. The levers on one side of the pivot stud 23 are shaped to form a pair of handles 65 25 and on the other side thereof are shaped to form relatively long and short jaws 26 and 27, respectively.

70 The short jaw 27, near its outer end, has in its inner edge portion a deep open notch-like seat 28 for releasably holding a grapple 29. This grapple 29 comprises a pair of laterally spaced arms 30 rigidly connected at their inner ends by an outwardly curved crosstie bar 31. The outer end portions of 75 the arms 30 are extended laterally toward each other to form a pair of spring-engaging hooks 32. The grapple 29 is detachably applied to the short jaw 27 by having its crosstie bar 31 removably mounted in the seat 28, 80 see Fig. 1, and with its arms 30 turned away from the long jaw 26. It may be here stated that the improved spring compressor will be provided with a plurality of interchangeably useable grapples of different sizes to engage 85 and hold valve springs of different diameters and lengths.

85 The lateral spacing of the arms 30 is such as to freely receive therebetween the valve spring 20 and the shape of the crosstie bar 31 90 is such as to extend radially outward from said spring to afford sufficient clearance to permit the outer end portion of the long jaw 27 to loosely extend between said bar and spring. The spring-engaging hooks 32 95 are adapted to be engaged by the upper end of the valve spring 20 at diametrically opposite points, as best shown in Fig. 2, and their opposing edges are curved to substantially the internal diameter of the spring 20 to afford 100 clearance therebetween for the boss 13. The outer end portion of the long jaw 26 is expanded to a width substantially the same as the grapple 29 and has in its outer end portion a deep relatively wide open notch 33 105 adapted to receive the valve stem 16. A shal-

low seat 34 for the washer 21 is formed in the inner face of the long jaw 26 with the notch 33 extended substantially therethrough.

To apply the tool to the spring 20 so that the same may be compressed and held with its upper end portion encircling the boss 13 while the valve stem 16 is being inserted through said spring and washer 21, and the pin 22 inserted through the hole provided therefor in the valve stem 16, said washer is placed in the seat 34 with the lower end of the spring 20 resting thereon and the upper end portion of said spring is placed within the grapple 29 under the spring-engaging hooks 32. The handles 25 are then operated to close the jaws 26 and 27 and compress the spring 20 between the washer 21 and the spring-engaging hooks 32 of the grapple 29. While the spring 20 is thus held compressed its upper end portion is inserted over the depending boss 13 and then the valve stem 16 dropped through said boss, spring and the hole in the washer 21, and the pin 22 inserted into the hole in the valve stem 16 provided therefor.

To detach the spring compressor from the spring 20, the handles 25 are first operated to open the jaws 26 and 27 to release the compressed spring 20 and disengage the long jaw 26 from the washer 21. A movement of the tool away from the block 7, until stopped by the engagement of the grapple arms 30 with the skirt 12, will disengage the hooks 32 from the engaged upper convolution of the spring 20 and position the same between the spring 20 and skirt 12 where the arms 30 may be removed by a downward movement of the tool. During this movement of the tool the long jaw 26 will be disengaged by the valve stem 16 which extends through the open notch 33 in said jaw. Obviously, the relatively long arms 30 make it extremely easy to handle a valve spring where there is a skirt closely positioned to the spring, as shown in the drawings, and particularly where the skirt is long.

In some instances, it might be easier to remove the tool from a released valve spring by first separating the levers of the tool at the pivot connection 23—24 and then removing the short jaw 27 from the engaged grapple 29. The separation of the jaw 27 from the grapple 29 may be accomplished by a compound lifting and turning movement of said jaw so as to position the same between the skirt 12 and crosstie bar 31 and then withdrawn from therebetween.

In case the space between the skirt 12 and spring 20 is such as to prevent the removal of the grapple 29 from the spring, said grapple may be detached from the spring by forcing its hook 32 rearward from under said spring and then moving the grapple 29 downward and outward to release the same from the spring 20.

The above described tool, while especially adapted as a spring compressor for use in replacing a valve spring as just described, is also well adapted for compressing a valve spring to permit the valve to be lifted from its seat. In this use of the spring compressor its long jaw 26 is inserted under the washer 21 and the grapple 29 positioned around the spring 20 with its hooks 32 inserted between the two convolutions of the spring 20 just below the skirt 12.

With the tool thus positioned, the handles 25 may be drawn together to compress the spring sufficiently to permit the withdrawal of the pin 22 from the valve stem 16 so that the valve 15 may be lifted from its seat. Obviously, the tool may be radially adjusted for springs of different lengths by inserting the pivot stud 23 into the different seats 24. While only two of such seats are shown, it is, of course, understood that others may be provided, if necessary.

What I claim is:

1. A spring compressor comprising a pair of pivotally connected levers having a pair of co-operating jaws, one of said jaws having a spring seat and the other thereof having a spring engaging-grapple forming an extension thereof in the direction of its opening movement, said spring seat and grapple being arranged to hold a spring to be compressed therebetween by a manipulation of the handles to close the jaws.

2. The structure defined in claim 1 in which the handles and grapple are arranged to be disassembled to permit the separation thereof from a released spring held thereby.

3. A spring compressor comprising a pair of pivotally connected levers, one of which has a long jaw and the other of which has a short jaw, said long jaw having a spring seat outward of the short jaw, and a spring-engaging grapple carried by the short jaw and extending outward over the spring seat whereby a spring may be compressed between the spring seat and grapple by a manipulation of the handles to close the jaws.

4. A spring compressor comprising a pair of pivotally connected levers, one of which has a long jaw and the other of which has a short jaw, said long jaw having a spring seat outward of the short jaw, and a spring-engaging grapple applicable to the short jaw and arranged to be held thereby over the spring seat whereby a spring may be compressed between the spring seat and grapple by a manipulation of the handles to close the jaws, said grapple being interchangeable with other grapples.

5. A valve spring compressor comprising a pair of jaws, one of which is relatively short and the other of which is relatively long, said jaw having a notch-like seat therein, means for operating the jaws, said long jaw having a valve stem passage and a seat for a

washer on the valve stem, and a spring-engaging grapple comprising a pair of laterally spaced arms and a crosstie bar rigidly connecting said arms to receive a spring therebetween, said crosstie bar being removably mounted in said seat and rigidly holding said grapple with its arms extending in the direction of the opening movement of the short jaws, said arms having spring-engaging

hooks on their outer ends arranged to engage 10 a spring seated on a washer in the washer seat in the short jaw.

6. The structure defined in claim 5 in which the jaws are adjustably connected to position said spring-engaging hooks different 15 distances from the long jaw.

In testimony whereof I affix my signature.
LOUIS TOUCHE
TTE.
